(57) **CLAIM**

The ornamental design for a delivery device with controls and cassette, as shown and described.

DESCRIPTION

FIG. 1 is an exploded leftward perspective view from the top of a delivery device with controls and cassette with the syringe connections cover of the cassette component attached;

FIG. 2 is an exploded rightward perspective view from the top of the device of FIG. 1 with the syringe connections cover of the cassette component unattached;

FIG. 3 is a top view of the delivery device component of FIG. 1;

FIG. 4 is a bottom view of the delivery device component of FIG. 1;

FIG. 5 is a right elevational view of the delivery device component of FIG. 1;

FIG. 6 is a left elevational view of the delivery device component of FIG. 1;

FIG. 7 is an enlarged front view of the delivery device component of FIG. 1, scaled at twice the size;

FIG. 8 is an enlarged rear view of the delivery device component of FIG. 1, scaled at twice the size;

FIG. 9 is an enlarged leftward perspective view from the top of the cassette component of FIG. 1, showing the syringe connections cover unattached;

FIG. 10 is an enlarged rightward perspective view from the top of the cassette component of FIG. 1, showing the syringe connections cover unattached;

FIG. 11 is an enlarged top view of the cassette component of FIG. 1, showing the syringe connections cover unattached;

FIG. 12 is an enlarged bottom view of the cassette component of FIG. 1, showing the syringe connections cover unattached;

FIG. 13 is an enlarged front view of the cassette component of FIG. 1, showing the syringe connections cover unattached;

FIG. 14 is an enlarged rear view of the cassette component of FIG. 1, showing the syringe connections cover unattached;

FIG. 15 is an enlarged right elevational view of the cassette component of FIG. 1, showing the syringe connections cover unattached; and,

FIG. 16 is an enlarged left elevational view of the cassette component of FIG. 1, showing the syringe connections cover unattached.

(Continued)

A characteristic feature of the design resides in the control elements of the handle and the removable cassette comprising containers.

The dash-dash broken lines shown in the figures depict portions of the device that form no part of the claimed design. The dash-dash broken lines in the drawings define the bounds of the claimed design and form no part thereof.
